[57] CLAIM

The ornamental design for an electric bass guitar, substantially as shown and described.

DESCRIPTION

FIG. 1 is a front elevational view of an electric bass guitar showing our new design;

FIG. 2 is an enlarged fragmentary front elevational view of the guitar body;

FIG. 3 is an enlarged fragmentary front, bottom and left side perspective view thereof;

FIG. 4 is an enlarged fragmentary right side elevational view thereof;

FIG. 5 is an enlarged fragmentary left side elevational view thereof; and

FIG. 6 is a rear elevational view of the guitar.

FIG. 1.

FIG. 2.

FIG. 4.

FIG. 6.

FIG. 3.

FIG. 5.
